[57] CLAIM

The ornamental design for a combined lamp and meter, as shown and described.

DESCRIPTION

FIG. 1 is a left, front perspective view of the combined lamp and meter showing my new design;

FIG. 2 is a fragmentary right side elevational view thereof on an enlarged scale, the shade being omitted for convenience of illustration;

FIG. 3 is a fragmentary rear perspective view thereof on an enlarged scale, the shade being omitted for convenience of illustration;

FIG. 4 is a top plan view thereof on a reduced scale.
